UNITED STATES PATENT OFFICE.

LOUIS FOLTAN AND ALEX OZSVÁTH, OF NEW YORK, N. Y.

TOOTH BRUSH AND PASTE SERVING RECEPTACLE.

Application filed July 5, 1922. Serial No. 572,858.

To all whom it may concern:

Be it known that we, LOUIS FOLTAN and ALEX OZSVÁTH, citizens of Hungary and the United States, respectively, residing at 5 New York, in the county of New York and State of New York, have invented certain new and useful Improvements in Tooth Brush and Paste Serving Receptacles, of which the following is a specification.

10 This invention relates to toothbrushes, having particular reference to a toothbrush in which are embodied paste feeding means.

15 The invention has for an object the provision of a novel form of toothbrush which embodies a receptacle for the paste, from which receptacle the paste can be readily fed to the brush.

20 More specifically speaking, the invention has for an object the provision of a paste ejecting device which will receive, and eject the paste from, the ordinary flexible tube in which such paste is commonly sold.

25 For further comprehension of the invention, and of the objects and advantages thereof, references will be had to the following description and accompanying drawings, and to the appended claims in which the various novel features of the invention 30 are more particularly set forth.

Fig. 1 of the drawings is a side view of our improved toothbrush.

Fig. 2 is a central longitudinal sectional view thereof at right angles to Fig. 1.

35 Fig. 3 is a transverse sectional view taken on the line 3—3 of Fig. 2.

Fig. 4 is a side view, partly in longitudinal section, showing the paste tube secured to the brush and ready for insertion in the 40 hollow handle.

Fig. 5 is a detail perspective view of the follower.

Fig. 6 is a detail perspective view of the brush shield.

45 Fig. 7 is a detail side elevation of the implement for cleaning the passage through the brush.

Fig. 8 is a fragmentary longitudinal section showing a modification of the discharge tube on the brush.

Referring now to the drawings the reference numeral 10 indicates a brush backing from which bristles 11 project. This backing 10 and bristles 11 may be constructed of the materials ordinarily employed in toothbrushes, the bristles being embedded in the

backing in the usual manner. The backing 10 is formed on one end with a short integral extension 10' whereby it is connected to a hollow handle forming a container for 60 the tooth paste.

As here shown the extension 10' is externally screw-threaded at its extremity as at 12 and is screwed into one end of a short nipple 13, the other end of the nipple bore 65 being of a size, and suitably threaded, to receive the usual threaded head 14 formed on the discharge end of all paste tubes such as that shown at 15 and on which the closing cap is ordinarily screwed. Extending longitudinally from the rear end forward through the brush backing 10 is a passage 16 which terminates a short distance from the forward end of the brush and has communicating with its forward end a short 70 tube 17, preferably of rubber which is fixed in the backing and projects among the bristles.

The body of the paste tube 15 is received within a cylindrical casing 20 into which 80 the rear end of the nipple 13 fits snugly, the front end of the casing 20 engaging a circumferential flange 21 on the nipple. The nipple 13 and casing 20 locked together by means of a coupling ring 22 which screws 85 on the threaded end of the casing 20 and has an inturned flange 22' engaging in front of the flange 21 on the nipple. The casing 20 preferably has an integral collar 23 formed thereon against which the coupling 90 22 abuts.

The paste tube, when full, substantially fills the casing 20 and is gradually compressed to force the paste out through the passage 16 and tube 17 by a suitable follower which in the present embodiment of the invention, is constructed and operated as follows: This follower comprises a short cylindrical thimble 25 across which a central longitudinal partition or web 26 extends, this partition being enlarged at the centre in the form of a hub 27. Fixed to opposite ends of the hub 27 are disks 28 which are of less diameter than the bore of the thimble, and which constitute the active 100 ends or faces of the follower. These disks 28 are here shown as secured to the hub 27 by screws 29 having their heads countersunk into the disks and which engage in opposite ends of the hub.

When the follower is in position the thimble 25 surrounds the casing 20 while

the disks 28 fit snugly therein, the ends of the web 26 being accommodated in two longitudinal slots 30 in the casing the follower is caused to travel along the casing by the following means:

Freely surrounding the casing is a barrel 32 of slightly less length than the casing 20, this barrel also surrounding the thimble 25. The latter is exteriorly screw threaded, while the barrel 32 is correspondingly interiorly screw threaded from end to end, the threads in the barrel engaging the threads on the thimble 25, the threads on the barrel and thimble being preferably left hand threads. It will be obvious then that if the barrel 32 is rotated without receiving axial movement, the follower will be caused to move along the casing 20, the follower being held against rotation with the barrel by the engagement 29 of the web 26 with the walls of the slots 30.

The barrel is held against axial displacement on the casing, at its forward end by the collar 23 and at its rear end by a cap 34 which is screwed on the projecting rear end 25 of the casing, it being understood that when the cap is screwed home it bears on the end of the casing and not on the end of the barrel. To cause the barrel to fit snugly on the casing a pair of collars 35 are fitted in opposite ends thereof to fill the space between the barrel and casing, it being obvious that the thimble can move along the space between these collars, or substantially the full length of the barrel.

In the use of our improved device, when a paste tube is to be inserted the coupling ring 22 is loosened, separating the brush proper, constituted by the parts 10, 11, from the hollow handle constituted by the parts 20, 32 etc. The previously exhausted paste tube is then disengaged from the nipple 13 and a new one attached thereto by screwing its head 14 into the nipple. As will be apparent, the follower 25, 28 etc. will be close to this end of the casing 20 and to obviate the necessity of threading the thimble 25 back along the barrel the cap 34 is removed and the casing is reversed the end on which the cap was screwed being engaged with the nipple 13 and the cap screwed on the other end, the follower being now in the rear end of the casing as will be understood. When the brush is to be used, barrel 32 is rotated advancing the follower, and forcing the paste through the passage 16 and tube 11 onto the bristles of the brush. As shown in Fig. 8 we may provide the brush with a discharge tube 17' constructed with a normally flat

discharge end, as shown, which thus remains closed when free from paste.

To clean the passage 16 we may employ a small brush 40, on the end of a rod 41 (see Fig. 6). The bristles may be protected by a guard 42 slipped over the forward end of the backing 10.

While we have illustrated and described a preferred embodiment of our invention it is to be understood that we do not limit ourselves to the precise construction shown and that various changes and modifications might be made therein without departing from the spirit and scope of the invention as defined in the appended claims.

Having thus described our invention what we claim as new and desire to protect by Letters Patent of the United States is as follows:

1. A device of the class described comprising a cylindrical casing adapted to contain a cleaning medium, said casing having each end open and being threaded at each end for selective attachment to a desired part, a double ended follower slidable in said casing, an interiorly threaded barrel rotatable on said casing and having threaded engagement with said follower, and a cap adapted to be selectively fixed upon either end of the casing.

2. A device of the class described comprising a cylindrical casing adapted to contain a cleaning medium, said casing being longitudinally slotted, a follower in said casing having a thimble fixed thereto and surrounding the casing, the attaching medium for the thimble and follower passing through the said slot, a barrel rotatably surrounding said casing and held against axial movement thereon, said barrel also surrounding and having screw thread engagement with said thimble.

3. A device of the class described comprising a cylindrical casing adapted to contain a cleaning medium, a double ended follower slidable in said casing, an exteriorly threaded thimble surrounding and slidable along said casing, said thimble being fixed to said follower by attaching means passing through longitudinal slots in said casing, and an interiorly threaded barrel rotatable on said casing and having threaded engagement with said thimble.

In testimony whereof we have affixed our signatures.

LOUIS FOLTAN.
ALEX OZSVÁTH.
